(57) **CLAIM**

The ornamental design for a lid for slush beverage container, as shown and described.

DESCRIPTION

FIG. 1 is a perspective view of the slush beverage container lid showing our design.

FIG. 2 is a perspective view of the lid similar to FIG. 1 but shown with its center button depressed.

FIG. 3 is a top plan view of the lid.

FIG. 4 is an elevational view of the lid which has the same appearance when viewed from any direction around the lid; and,

FIG. 5 is a perspective view of the lid similar to FIG. 1 but showing in broken lines a container with which the lid is used.

The broken lines are for illustrative purposes only and form no part of the claimed design.
